CONTROL DEVICE FOR SHOWER NOZZLES

Robert Hetherington, Sharon Hill, Pa., assignor
to Devices, Inc., a corporation of Pennsylvania

Application December 19, 1931, Serial No. 582,059

2 Claims. (Cl. 236—93)

My invention relates to temperature and water pressure control of shower bath spray nozzles.

My invention is intended to provide pressure controlling means within the body of a shower bath spray nozzle.

One purpose is to provide a shower head with a thermostatically controlled outlet to prevent water of too great a temperature from passing out through the openings in the spray nozzle, and 10 to bypass the hot water.

A further purpose is to construct a shower head with a detachable apertured cover having a baffle plate attached to the cover and a space between the cover and the baffle plate to allow 15 water to pass from the space and through the apertures in the cover plate.

A further purpose is to thermostatically control a baffle plate opening into a shower spray.

A further purpose is to automatically control 20 the pressure of a spray nozzle by discharging through a by-pass by means of a spring controlled valve.

A further purpose is to use both a spray nozzle outlet through suitable outlet apertures and a 25 by-pass outlet to relieve the spray nozzle from excessive pressure, or from excessively high temperature water, using pressure control means for the control of the two as desired.

My invention relates both to the methods involved and the apparatus by which the methods 30 may be carried out.

Further purposes will appear in the specification and in the claims.

Figure 1 is a sectional elevation of my improved 35 baffle plate construction within a shower head.

Figure 2 is a sectional view of Figure 1 taken on the line 2—2 thereof.

Describing in illustration and not in limitation and referring to the drawing:

40 I have preferred to illustrate a few forms only of the many that my invention may assume. I have therefore selected forms that are practical and efficient in operation and which well illustrate the principles involved.

45 While I have made one showing of my invention, I wish to have it clearly understood that it may be placed in any desired location above a bath tub or in a shower stall or at any angle as may be desired by the user or to meet the 50 conditions found present.

55 My shower head comprises a casing 10 with a reduced neck portion 11 threaded internally at 12 to receive the threaded extension of an ordinary shower head inlet fitting 13. A permanent pressure control plug 14 is inserted into a

threaded opening 15 in a wall 16 integral with the shower head 10. The maximum pressure is controlled by the extent to which this plug is screwed in.

Below the wall 16 a water chamber 17 is provided in the shower head and this chamber is closed at its outer face by an apertured cover plate 18. A gasket 19 of rubber or the like is placed between the cover plate 18 and the side and end walls 20 of the shower casing 10, and 10 the cover plate 18 and the gasket 19 are held in place against the shower casing by means of screws 21.

I form a baffle plate 22 connected with the cover plate 18. The baffle plate projects upwardly and into the shower casing. Between the baffle plate 22 and the cover plate 18 is a space or distributing compartment 23.

Water is admitted to the shower head through the inlet 13 and pressure controlling member 20 14 into the chamber 17.

In Figures 1 and 2 any suitable preferably spider support is provided within the body 10 of the shower head. It holds an end 24 of a bellows-like thermostat 25. The lower end of 25 the thermostat is swivel-connected at 26 to a closure 27 in a baffle plate 28. The baffle plate may be integral with the cover plate 18. The construction is effective as a valve giving or shutting off access to a compartment from which 30 apertures 29 discharge.

Upwardly directed guide pins 30 from the cover, fit into apertures 31 in the closure 27. As water enters the spray nozzle and becomes of too high temperature, it will cause the thermostat 35 to expand and to seat the closure 27 against the baffle plate.

The pressure is controlled by a spring pressed valve 32 set in the by-pass.

It would be evident that the pressure and temperature controls in Figures 1 and 2 cooperate, having unitary results in that the thermostatic control of access of water to the passage leading to the outlet spraying apertures, by which flow of excessively hot water is stopped, would 45 not be capable of delicate control if the closure member operated by the thermostat, and which is effective as a valve by being exposed to widely variant pressures. The by-pass with excessive water pressure prevents this within any limit of 50 water pressure which the designer cares to set. This relieves the thermostatic control not only from excessive variation in pressure but also from excessive absolute pressure and makes it 55 possible to design the thermostatic control with

definite knowledge of a maximum pull or push which it will be required to effect.

Though in slightly different ways, it will therefore be seen that the combined thermostatic and pressure controls cooperate notwithstanding any independence of movement whether the by-passing be temperature or pressure controlled, and whether the control of water passing to the apertures be correspondingly pressure controlled or 10 temperature controlled.

It will be obvious that when the hot water causes the thermostat to operate and effect closure of the baffle plate, the pressure will build up in the shower head and cause the spring 15 pressed valve 32 to open and the hot water will be discharged through the by-pass nozzle.

The control device, of course, though best placed in the shower head, need not necessarily 20 be located there, but could be a separate unit and placed behind a wall or elsewhere discharging excessively heated water through the tub nozzle or direct to the waste line.

In view of my invention and disclosure variations and modifications to meet individual 25 whim or particular need will doubtless become evident to others skilled in the art, to obtain part or all of the benefits of my invention without copying the structure shown, and I, therefore, 30 claim all such in so far as they fall within the reasonable spirit and scope of my invention.

Having thus described my invention, what I

claim as new and desire to secure by Letters Patent is:—

1. In a shower head, walls forming a chamber having spray openings, a valve located immediately behind the spray openings and adapted to 5 cut off flow through the spray openings, thermostatic means in the chamber carrying and operating the valve and bypass mechanism adapted to open by water pressure within the chamber to discharge water from the chamber. 10

2. In a thermostatic shower head a substantially flat shower face having water openings for distribution of the water spray, a substantially flat baffle plate, immediately behind the shower face extending over the major portion of the 15 shower face and movable toward and away from the shower face, there being openings in the baffle plate, guiding pins secured to the shower face extending through the openings, walls forming a valve seat cooperating with the edges of 20 the baffle plate, walls forming a water chamber behind the baffle for receipt of the water for the shower, a thermostatic element in the water chamber operatively connected to the baffle plate moving the baffle plate over the guiding pins 25 from its open to its closed position and from its closed to its open position, the space between the baffle plate and the water being reduced to a minimum so that the quantity of water of excessive temperature which can be retained in this 30 space is minimal.

ROBERT HETHERINGTON.
